UNITED STATES PATENT OFFICE

94,229

DESIGN FOR A SPOON OR SIMILAR ARTICLE

Robert E. Locher, Stapleton, Staten Island, N. Y.,
assignor to Rogers, Lunt & Bowlen Company,
Greenfield, Mass., a corporation of Massachusetts

Application March 9, 1934, Serial No. 50,987

Term of patent 14 years

To all whom it may concern:

Be it known that I, Robert E. Locher, a citizen of the United States of America, residing at Staten Island, in the county of Richmond, and State of New York, have invented a new, original, and ornamental Design for a Spoon or Similar Article, of which the following is a specification, reference being had to the accompanying drawing, forming part thereof.

In said drawing,

Fig. 1 is a plan view of a spoon showing my new design;

Fig. 2 is a fragmentary rear view showing the upper end of the spoon;

Fig. 3 is an edge view corresponding to Fig. 2 and Fig. 4 is a section taken on line 4—4 of Fig. 1.

The dominant feature of the design resides in the ornamental appearance produced at the end of the spoon handle (or the handle of a similar article of tableware) by the rounded and overlapped lip at the back of the central panel, as shown particularly in Figs. 2 and 3.

I claim:

The ornamental design for a spoon or similar article, substantially as shown and described.

ROBERT E. LOCHER.
